MEANS FOR CONNECTING COLLAPSIBLE
TUBES TO A PUMP DEVICE FOR DIS-
CHARGING THE CONTENTS THEREOFGeorge Frederick Gates, London, England, as
signor to Gestetner Limited, London, EnglandApplication July 9, 1948, Serial No. 37,836
In Great Britain July 10, 1947

2 Claims. (Cl. 222—80)

1

This invention relates to means for dispensing the contents of collapsible tubes and in particular to means for the purpose in question for delivering pasty or viscous inks to the inking cylinders of duplicating machines.

The usual way of dispensing the contents of collapsible tubes is to squeeze the tube by hand to expel a proportion of its contents and this has been the general practice in applying pasty or viscous inks to the inking cylinders of duplicating machines of the kind in which such cylinders are impermeable, although in some cases with such machines there has been associated means whereby such ink is delivered from a relatively rigid container furnished with a base adapted to function as a piston in order that by the displacement of the piston the contents of the container may be delivered to the inking cylinders of such machines.

The object of the present invention is broadly stated to provide improved means for dispensing the contents of collapsible tubes and to provide, in particular, means for the purpose in question adapted to be incorporated or incorporated in stencil duplicating machines of the kind above referred to.

A particular object of this invention is the provision of improved means for establishing an airtight connection between the nozzle and a collapsible tube and a pump, by means of which the contents of the tube may be drawn into the chamber of the pump and expelled therefrom by way of a delivery port or passage.

According to this invention there is provided, in a dispensing means comprising a pump for delivering viscous ink from a collapsible tube furnished with a nozzle, and in combination therewith, a hollow element communicating with the inlet port of the pump and terminating in a peripheral knife edge, and means adapted to bring the tube nozzle and said knife edge into abutment and drive said knife edge into the material of the nozzle at its outer extremity.

For instance in accordance with the invention below the usual screw-threaded portion of the nozzle of the collapsible tube there may be provided a recess or recesses adapted to be engaged by an element forming part of such means associated with a lever or equivalent mechanism arranged to impart motion to the element and to the nozzle in a direction parallel with its axis in order to bring the outer end of the nozzle against the peripheral sharp outer end of the hollow element communicating with the pump chamber associated with a lever or system of

2

levers or like mechanism for imparting motion to it.

Conveniently, the mechanism in question is such as to provide a toggle or wedging action.

Thus in accordance with the invention the means may comprise a lever, one arm of which is bifurcated and having in each of the elements of the bifurcated arm a slot engaging a pin on the side of a sleeve slidable axially on the hollow or tubular element furnished with a peripheral sharp edge and having an extension open at one side furnished with flanges adapted to enable the nozzle of the collapsible tube to be slid transversely into position so that the recesses provided on it are engaged by the flanges, so that by motion imparted to the sleeve by the lever the face of the nozzle will be brought firmly into contact with the hollow or tubular element provided with a sharp edge to secure a liquid-tight joint and in the extension of the sleeve there may be provided spring pressed members, for instance pins, adapted to engage a frusto-conical portion of the nozzle of the collapsible tube located in advance of the recess to facilitate appropriately positioning the nozzle with respect to the peripheral sharp edge of the hollow or tubular element.

The pump may be a piston pump and the axis of the chamber of the pump in which the piston operates is conveniently arranged to extend at right angles to the direction of the nozzle.

Any appropriate means may be provided to enable the piston of the pump to be reciprocated or actuated.

For instance there may be provided a lever or system of levers associated with a spring adapted to constrain the piston towards one end of its stroke, that is to say to effect delivery of the contents of the pump chamber while permitting the piston to be moved in the reverse direction in opposition to the spring.

As applied to the inking mechanism of a duplicating machine the outlet or delivery of the pump may be connected to an ink delivery tube adapted to extend in a direction parallel with the axes of the inking cylinders of the duplicating machine and relatively adjacent to one of the ink distributing rollers associated therewith and having a plurality of ports spaced apart in the direction of its length.

Conveniently, where the device is designed to be associated with a machine, for instance a duplicating machine, of the known type furnished with a plurality of ink impermeable inking cylinders engaged in side members forming part of

the machine frame, the device may be arranged to be detachably engaged with the frame and in this case a hole may be provided in one of the side members through which the ink delivery tube will pass and a hole in the opposite side of the frame in which a spigot provided on the ink delivery tube may be detachably engaged. To facilitate securing the device in its appropriate position with respect to the frame a spring pressed catch connected with a lever may be associated with the device at a position adjacent to the pump chamber, the catch being formed, for instance, on the end of the lever also associated with the chamber of the pump or its housing and furnished conveniently with a hooked end so that in pulling upon the end of the lever it will be moved about its pivot to disengage the catch from a recess provided in the side member of the frame.

If desired the lever or like mechanism by which the pump is operated may be arranged in driving connection with the means imparting motion to the inking cylinders of the duplicating machine.

Generally, however, it is desirable to arrange that the pump may be operated independently of such driving means and in accordance with the judgment of the operator of the machine.

A construction in accordance with the invention is illustrated by way of example in the accompanying drawings which illustrate the application of connecting means according to the invention for the purpose of delivering pasty or viscous inks to the chamber of a suction pump from a collapsible tube.

In the drawings:

Figure 1 is a view showing certain parts in the position which they will assume in entering the neck of the collapsible tube;

Figure 2 shows the parts in the position in which they engage the tube which has a neck in the form illustrated in Figure 3 with its screw cap removed;

Figure 4 is a view in section on a plane indicated by the line IV—IV of Figure 2 viewed in the direction of the arrows;

Figure 5 is a view in section on a plane indicated by the line V—V;

Figure 6 is a perspective view showing the combination of a pump with the collapsible tube and securing means of Figures 1-5.

The construction of the means is clearly seen from Figures 1, 2, 4 and 5, the form of the neck of the tube being shown in Figure 3.

In this figure it will be seen that there is provided on a neck or nozzle portion of the tube 3 a screw thread 5 adapted to be engaged by a cap 6, the screw-threaded portion being immediately below the nozzle portion 1 provided with a discharge or delivery aperture surrounded by a wall of such thickness to provide a seating into which the sharp edge of a tube forming part of a dispensing device may be forced as shown in Figures 2 and 4 by engaging a circumferential recess 8 in the tube neck with a lip 9 of a jaw 10, see Figure 4, formed on the end of an annular member 11 slidable on the tube 12, the lower extremity of which is furnished with a bevelled or sharp edge 13 adapted to be forced into the wall surrounding the nozzle of the tube.

For effecting this operation there is provided a bifurcated lever 14 furnished with a finger piece 15 and slots 16 engaging pins 17 on the annular member 11, on which is mounted a spring 18 operating to urge the points of pins 19 into position to engage against the inclined surface 20 of the upper portions of the tube 3. The lever 75

14 is pivoted by screws 21 on an extension 22 from a housing 23 of a pump, not shown.

Figure 3 shows a collapsible tube 3 suitable for use in conjunction with the apparatus of this invention, comprising a nozzle 1 formed intermediate its length with a threaded portion 5 for engaging a cap 6, the threaded portion 5, defining, with the main body of tube 3, a recess 8 for the purpose hereinbefore described.

Figure 6 shows a combination of a collapsible tube, securing means and a pump, the former two being as shown in Figures 1-5. The pump comprises a body or casing 1, delivery tube 2 and piston rod 41, and is attached to the side wall or frame 4 of a duplicating machine (not shown) by a catch lever 46 provided on the pump body. Lever 46 is constrained by a torsion spring 47 to cause its curved end 48 to engage a slot 49 in a plate 50 secured to frame 4. Piston rod 41 is arranged to be actuated by a lever 29 furnished with a slot 30 engaging a pin 31 on one arm of a lever 32 pivoted by a screw 33 to frame 4 and constrained into the position shown by a spring 34. Lever 32 is adapted to be moved about its pivot by the displacement of a lever 35 in opposition to a spring 36 about pivot 37 to bring a heel 38 on lever 35 into engagement with an abutment 39 on lever 32 and by further motion of lever 35 to impart motion to lever 29 which is in engagement with a recess 40 in piston rod 41.

The arrangement of heel 38 and abutment 39 is provided so that lever 35 can lie back and conform with the upper edge of frame 4 when not in use to present a streamlined appearance, while being brought to an upright position for ease of manipulation before actuation of piston rod 41 commences.

On lever 29 there is a pin 42 arranged to cooperate with an elevation 43 on a lever 44 pivoted to frame 4, the free end of which engages in a recess 45 near the top of the pump body and constrains the latter into the appropriate position for engagement of catch lever 46. When the pump is being attached to the duplicating machine, pin 42 is in the position shown and its purpose is to contact elevation 43 on lever 44 and hold the latter up in such a position that it does not obstruct attachment of the pump; when lever 35 is subsequently rotated to actuate piston rod 41 it moves lever 39 so that pin 31, as it moves downwards, acts on elevation 43 and causes lever 44 to thrust the pump home, thereby correcting for any faulty initial attachment.

I claim:

1. In a dispensing device comprising a pump for delivering viscous ink from a collapsible tube furnished with a nozzle comprising an annular wall having behind the usual screw threaded portion a circumferential recess, and in combination therewith, a hollow element communicating with the inlet port of the pump and terminating in a peripheral knife edge, and means adapted to bring the tube nozzle and said knife edge into abutment and drive said knife edge into the material of said annular wall at its outer extremity, said means comprising a lever, one arm of which is bifurcated and having in each of the elements of the bifurcated arm a slot engaging a pin on the outside of a sleeve slidably axially on said hollow element and having an extension open at one side furnished with flanges adapted to enable the nozzle of the collapsible tube to be slid transversely into position so that the circumferential recess provided on it is engaged by the flanges, and so that by motion imparted to the sleeve by

the lever the material of the extremity of said annular wall will be brought firmly into contact with said hollow element to secure an airtight joint.

2. In a dispensing means comprising a pump for delivering viscous ink from a collapsible tube furnished with a nozzle comprising an annular wall terminating in a circular substantially flat end surface, and in combination therewith, a hollow element communicating with the inlet port of the pump and terminating in a peripheral knife edge, means for engaging said tube to hold the end surface of the tube nozzle and said knife edge in abutment, and means operative to drive said knife edge into the material of said annular wall at its outer extremity.

GEORGE FREDERICK GATES.
